US00D817251S

(12) **United States Design Patent** (10) **Patent No.:** **US D817,251 S**
(45) **Date of Patent:** **** May 8, 2018**

(54) **DRONE**

- (71) Applicant: **Samsung Electronics Co., Ltd.**, Suwon-si (KR)
- (72) Inventors: **Eunyoung Kim**, Seongnam-si (KR); **Hayoul Jung**, Yongin-si (KR)
- (73) Assignee: **SAMSUNG ELECTRONICS CO., LTD.**, Suwon-si (KR)
- (**) Term: **15 Years**
- (21) Appl. No.: **29/581,360**
- (22) Filed: **Oct. 18, 2016**

(30) **Foreign Application Priority Data**

- Apr. 19, 2016 (KR) 30-2016-0018738
- (51) **LOC (11) Cl.** **12-07**
- (52) **U.S. Cl.**
USPC **D12/325**; D12/16.1
- (58) **Field of Classification Search**
USPC D12/3, 16.1, 319-345; D21/436-455
CPC B64C 39/024; B64C 2201/108

(57) **CLAIM**

The ornamental design for a drone, as shown and described.

DESCRIPTION

FIG. 1 is a top perspective view of a drone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is a top perspective view of the drone of FIG. 1 shown in an alternate configuration of use.

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a bottom perspective view thereof.

The dashed broken lines in the drawings represent portions of the drone that form no part of the claimed design.

The dot-dash broken lines in the drawings represent a boundary line that forms no part of the claimed design.

1 Claim, 16 Drawing Sheets
